W. B. NEHER

APPARATUS FOR THE MANUFACTURE OF ROUGH TEXTURE BRICK

Filed August 1, 1925

Patented Apr. 13, 1926.

1,580,154

UNITED STATES PATENT OFFICE.

WILLIS B. NEHER, OF DECATUR, ALABAMA.

APPARATUS FOR THE MANUFACTURE OF ROUGH-TEXTURE BRICK.

Application filed August 1, 1925. Serial No. 47,622.

To all whom it may concern:

Be it known that I, WILLIS B. NEHER, a citizen of the United States of America, residing at Decatur, in the county of Morgan and State of Alabama, have invented 5 certain new and useful Improvements in Apparatus for the Manufacture of Rough-Texture Brick, of which the following is a specification.

10 My invention relates to an apparatus particularly intended for the production of a novel type of rough texture brick in accordance with the process forming the subject matter of a companion application filed of 15 even date herewith, Serial No. 47,621, which brick is characterized by having its face provided with irregular flattened relief patches that give it a pleasing variable immethodical outline corresponding somewhat 20 to that of rotten stone.

My present invention is intended to illustrate a mechanism especially adapted for producing brick with such a face and to this end it utilizes any of the existing means 25 for providing the longitudinal scores on one or more faces of the brick column in combination with means, however operated, for transversely scoring the top scored surface of the column and means to roll such surface to flatten the raised portions and bond 30 the displaced patches to the column.

It is to be understood that the mechanism, which is hereinafter described in detail and which is illustrated in its preferred embodiment only in the accompanying drawings, 35 may be widely varied without departure from the essential features required for producing the proposed "rug" surface on the finished brick.

40 According to the drawings:—

Fig. 1 illustrates in plan view a portion of an auger mill with the clay column expelled therefrom resting upon the measuring belt of a cutting table and being subjected to a transverse scoring operation and a rolling operation prior to being cut, the cutting mechanism not being shown.

Fig. 2 is a side elevation of Fig. 1.

Fig. 3 is an enlarged cross-sectional view 50 taken on the line 3—3 of Fig. 1.

Fig. 4 is a cross-sectional view along the line 4—4 of Fig. 3.

Similar reference numerals refer to similar parts throughout the drawings.

55 In the embodiment of my invention illustrated, I show conventionally an auger mill

having the usual die 1 about which is clamped a top scoring device 2 and side scoring devices 3, which may be of any customary or usual construction. These scoring devices produce 60 upon the sides and top of the column 4 the usual and customary longitudinal parallel scores 5 customary in vertically scored rough texture brick. In the usual manner the column passes onto the measure belt 6 of 65 the cutting table 7. This belt is mounted on idlers 8 and 9 suitably journaled in the table so that the upper flight of the belt travels between the side boards 10 on the table. The idler 8 is mounted fast upon a shaft 11 of 70 which overhangs at one side of the table and has fast on its overhung end a large sprocket wheel 12. A sprocket chain 13 leads from the sprocket 12 to a small sprocket 14 mounted at one end of a shaft 75 15 suitably journaled in bearings 16 in a bracket 17 on a stand 18 connected to the table in any suitable manner or rigidly supported adjacent thereto. The shaft 15 carries fast thereon a bevelled gear 19 which meshes with a bevelled gear 20 on a shaft 21 at right angles to the shaft 15 and mounted in an elongated bearing 22 on the bracket 17. On the overhung end of the shaft 21 I mount a crank disk 23 having a 80 pin 24 to which a connecting rod 25 is coupled at one end, its other end being connected between the lugs 26 on the frame of a reciprocating carriage 27 supported on 85 each side by two pair of rollers 28 which travel between horizontal tracks 29 formed by spaced connected bars disposed transversely of and above the scored column 4. The tracks are mounted on brackets 30 of 90 any suitable character, preferably attached to the side boards 10 and the carriage has depending below it and attached to its sides a U-bar 31 parallel with the column 4 and having depending from its under face a series of adjustable screws 32 pointed at 100 their lower ends and adapted to transversely score the longitudinally scored top surface of the column when the carriage is reciprocated by the crank disk. The carriage frame 27 is preferably formed by a metal 105 plate having end notches which receive the rollers 28 which are mounted on pins 33 that traverse the notches and have their ends secured in the plate. The upper track bars are cross braced overhead by the flat bar 34 110 at one end and by the arched bar 35 at the end near the crank disk.

115

It will be noted that the carriage will move with very little friction in its guide tracks and that the transverse scoring of the column face does not interpose a heavy duty on the drive which would cause a slippage of the column 4 on the measuring belt 6. This enables me to utilize the movement of the column to apply the transverse scoring thereto so that it will be uniform.

To the right of the cross scoring mechanism I mount journal brackets 36 in which I pivot the arms 37 which in their free ends are adapted to receive the axis 38 of a roller 39 which is adapted to rest on and to roll flat the raised portions left by the intersecting scores on the top surface of the column. This roller has the usual fabric cover 40 to give a rough texture surface to the portions which are rolled flat in relief relative to the main body of the column. Beyond the roller the finished column passes to the cutting reel, not shown, but which in the usual manner will subdivide the column into bricks having their faces with the "rug" texture finish which is produced by my process in the top surface of the column.

While I have shown and prefer to use a mechanical drive for the transverse scoring which is co-ordinated with the movement of the column, nevertheless my invention contemplates in its broadest aspects the combination of mechanisms, however operated, which will produce upon any desired surface of the column, intersecting diagonal scorings and mechanism for rolling the resultant irregular surface.

In operation, as the clay column 4 is expelled from the die 1, the scoring devices 2 and 3 will apply to the top and side surfaces of the column longitudinal scorings 5 in the usual manner, and the column thus scored will pass onto and by its weight will drive the measuring belt 6. From this belt, through its forward idler 8 and the transmission mechanism described, the carriage 27 will be reciprocated back and forth with a travel which will cause its scrapers 32 to traverse the full width of the top face of the column except about a quarter of an inch along each side to avoid injury to the corners of the column. Due to the fact that the transverse scoring takes place contemporaneously with the longitudinal movement of the column, these scorings are diagonal and not at right angles to the longitudinal scorings 5. As the scoring points pass transversely across the ridges left by the scorings 5, they tear away and displace sections of such ridges, leaving the main body portion of the column exposed and displacing the ridge section on the face of the column. In this way the surface of the double scored

face is not only broken into patches by the intersecting scorings, but raised portions thereof are entirely displaced in a manner which is immethodical and variable. When the raised portions are rolled a finished surface is produced formed by flattened high faces of irregular outline and of variable position which rise in relief above the main body surface of the column and give a surface or texture quite similar to rotten stone.

I prefer a roller 39 as the most suitable means for finishing the double scored face of the column because it is necessary to apply enough pressure to the detached portions of the top surface to obtain a satisfactory bond with the main body portion of the column and a roller is the most suitable and practical means to attain this end, though any smoothing means might produce an approximate effect.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a brick machine, mechanism for longitudinally scoring a column of brick material, a mechanism for transversely scoring a longitudinally scored face of the column, and presser mechanism to flatten down the doubly scored face of the column.

2. In a brick machine, in combination with mechanism for producing a longitudinally scored brick column, of mechanism for transversely scoring and means for rolling the doubly scored surface of the column.

3. In a brick machine, the combination with mechanism for producing a longitudinally scored brick column, of mechanism co-ordinated with the movement of the column to transversely score it, and means to smooth the doubly scored surface of the column.

4. In a brick machine, a cutting table for a brick column comprising a measuring belt, mechanism for delivering a brick column onto said belt to drive it, means to longitudinally score the column, means to transversely score the column, means to drive said latter means from the belt, and means to roll the transversely scored surface of the top.

In testimony whereof I affix my signature.

WILLIS B. NEHER.
